(57) **CLAIM**

The ornamental design for a collapsible target trainer, as shown and described.

DESCRIPTION

FIG. 1 is a front elevational view of a collapsible target trainer showing my new design thereof;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a left side perspective view thereof.

The broken line showing of a net and handle is included for the purpose of illustrating environmental structure and forms no part of the claimed design.
